DOOR LATCH AND INTERLOCK

Oliver H. Beymer and William H. Nesbit, Pittsfield, Mass., assignors to General Electric Company, a corporation of New York

Application December 2, 1947, Serial No. 789,300

2 Claims. (Cl. 292—146)

1

This invention relates to door latches and more particularly to door latches of the interlocking type whose operation prescribes the sequence of opening and shutting a series of adjacent doors.

It is often required where two adjacent doors are separated by a door jamb, that one of the doors have a concealed lock and that this lock should be available only by opening the other door. Also, the lock and latch must be made fool-proof so that it cannot be jimmied out of the locked position when both doors are closed. It is difficult to provide an ordinary type of latch which will satisfy the prescribed conditions. First of all the material from which the door and door jamb is constructed is usually thin making it impossible to recess handles, knobs or stops. Also, the clearance between the door and door jamb is usually made as small as practical thus allowing little or no space for a handle, stop or latch. In the case where the two doors are separated by a partition it would be impossible to reach the concealed lock without having a hand hole in the partition—safety requirements preclude this possibility.

An object of this invention is to provide an improved, simple and inexpensive system for mechanically locking a plurality of adjacent doors so that the operation of any door is dependent upon the adjoining ones.

Another object of the invention is to provide in such a system a means for mechanically locking a plurality of doors using concealed locks for all but one, or the master door.

Still another object of the invention is to provide a simple and improved means for mechanically interlocking a plurality of doors in such a way as to prescribe a certain sequence of operation in opening the doors and the reverse sequence in closing the doors.

The invention will be better understood from the following description taken in connection with the accompanying drawing and its scope will be pointed out in the appended claims.

Fig. 1 shows a plan view of a unit sub-station composed of three compartments having a door in the front of each one. Figs. 2, 3, and 4 show a plan view, side elevation through the section 3—3 of Fig. 2, and back elevation respectively of a preferred form of the latch mechanism. Fig. 5 is a plan view of the doors ajar. Fig. 6 is a plan view of an alternative latch construction.

Fig. 7 is a plan view of a mechanism for interlocking the doors. Fig. 8 is a front elevation of the same device. Fig. 9 is a side elevation of the interlocking mechanism through the section

9—9 of Fig. 8. Fig. 10 is a side elevation through the section 10—10 of Fig. 8. Fig. 11 is a plan view of an alternative mechanism for interlocking the doors. Fig. 12 is a side elevation of this interlocking device through the section 12—12 of Fig. 11.

Referring now to the drawing there is shown in Fig. 1, by way of example, a unit sub-station 1 composed of three compartments 2, 3, and 4 each having respectively a door 5, 6, and 7. Door 5 is the master door—sub-door 6 can only be opened after door 5 has been opened; adjacent door 7 cannot be opened before sub-door 6. Thus, the opening operation must start at the master door 5 and continue, in the illustrated case, sequentially to the left. Similarly, it will be shown that the closing operation must follow the reverse order. Fig. 2 shows a preferred form of the interlocking mechanism between the master door 5 and sub-door 6 in an enlarged view. Master door 5 is supported by hinge 8, and both doors, 5 and 6 close against the same door jamb 9. Master door 5 may be locked by some external locking mechanism (not illustrated) whereas the sub-doors are held closed by a concealed latch 10 which has a cylindrical body or bolt 11 with a taper at one end 12 and at the other end, two handles or arms 13 and 14 which may be an integral part of the body 11. The latch 10 passes through the door jamb 9 into a hole in the sub-door 6. Master door 5 is slotted so that the latch 10 passes through it, but does not prevent door 5 from opening. The handles 13 and 14 are approximately perpendicular to each other so that when latch 10 is in the closed position handle 13 lies in the horizontal and extends toward the rear of door 5 where it rests in a notch 15 of a notched locking plate 16. The side of the notch 15 is sloped slightly so as to wedge the bolt 19 farther into the locked position in door 6. When the doors 5 and 6 are closed handle 14 extends approximately vertically upward, and master door 5 closes flush against the bolt 10, thus preventing rotation of the latch bolt 10 and consequently it cannot be jimmied out of the locked position since vertical handle 14 will not allow the horizontal handle 13 to be moved from the notch 15.

In order to operate the latch 10 it is first necessary to open the master door 5; rotate the handle, as shown in Fig. 3, so that the horizontal handle 13 is raised out of the notch 15 and clears the notched locking plate 16. The latch bolt 10 may then be moved to the right until the stop 17 strikes the door jamb 9 as shown in Fig. 5. The stop 17 also prevents the removal of latch bolt 10

from the door jamb 9. Sub-door 6 may now be opened as shown in Fig. 5.

When the bolt 10 is in the open position master door 5 cannot be closed because of interference with handle 14.

A variation of this arrangement for locking is shown in Fig. 6. This is similar to the method already disclosed except that a wedge block 18 may be made an integral part of door 5 so that when door 6 is closed and latch 19 is in the closed position the wedge 18 presses against the latch bolt 19 holding it securely locked and preventing it from being jimmied out of the locked position. When the latch bolt 19 is in the open position door 5 cannot be closed because the wedge block 18 strikes against the latch bolt 19 as shown in Fig. 6. This alternative construction has the advantage of using a simpler latch, but the preferred form of the invention has the advantage of having the latch and locking mechanism independent of the door.

It can be seen that the latch bolts 10 and 19 can be returned to the closed position without closing sub-door 6. Therefore, master door 5 can be closed while sub-door 6 is still open. In order to remedy this situation some form of interlock mechanism which makes it extremely difficult to close the master door 5 without first closing sub-door 6 is necessary. Two forms of such interlocking mechanisms are shown in Figs. 7-12.

Door jamb 9 in Fig. 7 is provided with a bar 20 and a block 21 to which is attached a rod and plate assembly 22 by means of a pin 23 and a shim 24. The rods on assembly 22 extend through slots 25 and 26, Figs. 9 and 10, in door jamb 9. When doors 5 and 6 are both closed assembly 22 is in a horizontal position and the rods engage notches 27 and 28 in doors 6 and 5. When master door 5 is opened (this must be done to release the latch bolt for door 6—as previously explained) assembly 22 remains in a horizontal position. But when the latch bolt for door 6 is released and door 6 is opened, the assembly 22 drops by gravity, since pin 23 is offset from the center line of door jamb 9, from the horizontal position shown in Fig. 9 to the inclined position. If door 6 is closed first assembly 22 "rides up" on the slope of notch 27 and returns to a horizontal position; thus, lining up the other end of assembly 22 with notch 28 allowing door 5 to close. But if it is attempted to close door 5 first the edge of door 5 will strike against assembly 22 which is in the inclined position shown in Fig. 8 making it impossible to close door 5. Any series of doors may be interlocked in this fashion.

Another arrangement for interlocking the doors is shown in Figs. 11 and 12. Door 6, in Fig. 11 is provided with a pin 29 which, when door 6 is closed, passes through the opening 30 in the door jamb 9. The pin 29 forces a striker plate 31 which is an integral part of an interlock 32, as shown in Fig. 12, toward the back of a guard 33.

Also as shown in Fig. 12 this moves the interlock 32 which is pivoted about pin 34 so that notch 35, which has a diameter slightly larger than that of the latch 10, will correspond with the hole 36 through the door jamb 9. Thus, allowing latch bolt 10 to be moved to the left and locking sub-door 6.

When door 6 is opened pin 29 is withdrawn

from opening 30 and due to the location of the center of gravity of interlock 32 it falls into the position shown by the solid outline of the interlock 32 in Fig. 12. The hole 36 in the door jamb 9 is partially covered by the interlock 32 so that it is impossible for the latch bolt 10 to be placed in the closed position. It can only be moved to the left when hole 36 and notch 35 are in correspondence and this is only achieved when sub-door 6 is closed.

The arrangements previously described for locking and interlocking two adjacent doors are not limited to the case used in the preceding discussion where both doors close against the same door jamb. Consider doors 6 and 7 as shown in Fig. 1. Door 7 closes against door jamb 37, but door 6 is attached to door jamb 37 by hinge 38. The latch bolt 10 passes through both the door jamb 37 and the hinge 38, and the doors 6 and 7 are interlocked in the same way as doors 5 and 6. Thus any series of doors can be locked and interlocked in this manner.

While there have been shown and described particular embodiments of the invention, it will be obvious to those skilled in the art that changes and modifications can be made without departing from the invention, and, therefore, it is aimed to cover all such changes and modifications as fall within the true spirit and scope of the invention, as claimed.

What we claim as new and desire to secure by Letters Patent of the United States is:

1. An interlocking door latch system for mounting in a door jamb which is between a hinged master door cooperating with one side of said jamb and a hinged sub-door which closes against the other side of said jamb, comprising a bolt slidable along and rotatable about its axis in said jamb, said sub-door having a hole for receiving an end of said bolt when said sub-door is closed and said bolt is slid toward said sub-door for latching said sub-door closed, a pair of arms attached to the other end of said bolt and extending at right angles to the axis of said bolt and at right angles to each other, and a notched plate associated with said door jamb, the notches in said plate being so located and proportioned as to receive one of said arms in a position perpendicular to said master door only when said bolt has been moved along its axis into its latched position of said sub-door, said arms and plate cooperating to prevent closure of said master door when said bolt is in any other axial position, said notch preventing movement of said bolt from its latching position of said sub-door except when said master door is open.

2. An interlocking door latch system as defined in claim 1 combined with additional interlock means for preventing closure of said main door until after said sub-door has been closed.
